Patented Dec. 1, 1914.

UNITED STATES PATENT OFFICE.

REINHOLD B. MARSCHKE, OF MISSOULA, MONTANA.

SHINGLE.

1,119,439.

Specification of Letters Patent.

Patented Dec. 1, 1914.

Application filed January 4, 1913. Serial No. 740,217.

To all whom it may concern:

Be it known that I, REINHOLD B. MARSCHKE, citizen of the United States, residing at Missoula, in the county of Missoula 5 and State of Montana, have invented certain new and useful Improvements in Shingles, of which the following is a specification, reference being had therein to the accompanying drawing.

10 This invention relates to roofing and has special reference to a roof of a shingle type which may be laid in layers each portion of a row being integrally connected.

Another object of this invention is the 15 production of a roofing of the shingle type which is provided with means carried by the shingles whereby the same may be readily adjusted without the use of a measuring instrument.

20 With these and other objects in view this invention consists in general of certain novel combinations, constructions, and arrangement of parts as will be hereinafter fully described and illustrated in the accompanying 25 drawing and specifically claimed.

In the accompanying drawing: Figure 1 is a top plan view of the roofing showing one form of shingle. Fig. 2 is a top plan view of the roofing illustrating a shingle of 30 a different shape. Fig. 3 is a perspective view of a single shingle. Fig. 4 is a perspective view of a modified form of shingle. Fig. 5 is an edge view of one of the shingles. Fig. 6 is an edge view of a number of shingles 35 illustrating how the same are laid.

Referring to the accompanying drawing by numerals it will be seen that the shingles consist of bodies 1 which are connected together by means of integrally formed lugs 40 2 and 3. Positioned in alinement with the lugs 3 are a plurality of apertures 4 through which the attaching means are adapted to pass. Located adjacent the lugs 3 are a plurality of channel portions 5 which extend 45 transversely of the shingle and are positioned upon each side thereof. At the outer end of the shingle there are provided a plurality of spurs 6 which are adapted to fit within one of the channel portions 5. These 50 spurs are formed upon each side of the shingles the same as the channels 5.

The shingles are formed in strips of considerable length and are formed of a number of sheets of paper upon which a composition of cement is placed whereby the 55 paper will be imbedded in the cement. By

forming the channels and spurs upon each side of the shingle a row may be laid without attention to which side is being placed down. By use of these channels 5 and the 60 spurs 6 it will be possible to place the spurs within one of the channels 5 for holding the row evenly while the same is being attached and it will also form a means for placing the row in this even position without the 65 aid of a measuring instrument.

It will, of course, be seen that these shingles may be formed separately as indicated in Figs. 3 and 4 in which case the shingles are provided with the usual body 7 and 70 spacing lugs 8 formed thereon. By use of these spacing lugs it would be possible to place each shingle evenly in position without the aid of a measuring instrument since the lugs formed upon each shingle are 75 evenly spaced. These shingles are also provided with the channels 5 and lugs 6 whereby they will form a secondary means for placing the shingle evenly upon a support, and the shingles are also formed of a similar 80 composition above described.

Since the lugs 8 connect a row of shingles or else abut against each other, it would be impossible for the weather to beat up under the shingles and rot the same, or in 85 the course of a short time cause the same to become worn and allow the moisture to enter the house.

It will be noted that this shingle may be formed of any suitable material such as slate 90 or wood without departing from the spirit of the invention, since the mechanical construction of the device is not departed from. The shingle may be formed of wood and may receive the securing means without 95 danger of the shingle being split by the nails or screws forming the securing means; and furthermore since the lower lugs will abut against each other the weather will be prevented from beating up under the shingles. These lugs will constitute a means for placing the shingles in alinement and will 100 also cause the inner ends of the shingles which are positioned under the shingles of the outer row or layer to be comparatively 105 dry since it will be impossible for rain or snow to have access thereto. However, if any dampness should be positioned or should seep between the edges of the shingles, sufficient air space is allowed to facilitate the 110 drying out of the shingles whether the same is made of concrete or wood and thus pre-

venting the shingles from rotting out at the edges; this will increase the life of the shingle and will also allow the roof to remain comparatively dry and will also prevent any seepage of water when the same is wet. These functions are performed by the lower lugs fitting snugly together and thus eliminating any room or space through which moisture could pass.

10 Having thus described the invention what is claimed as new, is:—

A shingle comprising a body, a pair of rectangular spacing lugs integrally formed upon the two side edges of said body, said lugs formed evenly upon the side edges so that the lugs upon one side will be in alinement with the lugs upon the opposite side, said lugs adapted to space the shingles apart so as to allow ventilation whereby moisture therebetween will quickly dry, said lugs also adapted to abut for alining the shingles, the lower lugs adapted to prevent a greater portion of the weather from beating under the shingles thereby preventing the shingles from warping and rotting due to excessive moisture along the side edges thereof.

In testimony whereof I hereunto affix my signature in presence of two witnesses.

REINHOLD B. MARSCHKE.
